UNITED STATES PATENT OFFICE.

HENRY O. EVANS, OF PHILADELPHIA, PENNSYLVANIA, ASSIGNOR TO
THOMAS DEVLIN & CO., OF PHILADELPHIA, PENNSYLVANIA, A FIRM.

FOOD-CHOPPER.

SPECIFICATION forming part of Letters Patent No. 711,837, dated October 21, 1902.

Application filed May 11, 1901. Serial No. 59,821. (No model.)

To all whom it may concern:

Be it known that I, HENRY O. EVANS, a citizen of the United States, residing in the city and county of Philadelphia, State of Pennsylvania, have invented a new and useful Improvement in Food-Choppers, of which the following is a specification.

My invention consists of an improved construction of a food-chopper wherein I provide novel means for enabling the cutting device and its adjuncts to be withdrawn from the casing in an assembled condition in an expeditious manner, whereby the parts can be frequently inspected and cleaned, according to requirements.

It also consists of a novel construction of devices for locking the parts in assembled position.

It also consists of a novel construction of a pivotal jaw for holding the bracket which supports the casing or body of the chopper in position, whereby the device is rigidly held to the table or bed during the action of the chopper.

It further consists of novel details of construction, all as will be hereinafter fully set forth, and particularly pointed out in the claims.

Figure 1 represents a vertical sectional view of a food-chopper embodying my invention, certain of the parts being shown in elevation. Fig. 2 represents an end elevation of the chopper. Fig. 3 represents a plan view of the locking device seen in Fig. 2.

Similar numerals of reference indicate corresponding parts in the figures.

Referring to the drawings, 1 designates the chopper, consisting of a casing or body 2, having the mouth or inlet 3, said casing being supported upon the bracket or post 4, which is secured to a table, bed, or other support by means of the stationary jaw or jaws 6 and the movable jaw 7, which has the thumb-screw 10, bearing upon a recess in the under portion of said movable jaw, the extremity of said thumb-screw being seated in said recess or channel.

11 designates a crank or other handle having the squared or polygonal seat 12 and the opening 13 in the upper portion thereof, in which seat and opening, respectively, are re-

ceived the parts 14 and 15, of corresponding contour, which extend from the forcer 16, which preferably consists of a worm or spiral 17, which is adapted to force the material to be chopped along the bottom 18 of the casing 2. The bearing 19 of the handle 11 is retained in position within the casing by means of the washer 20 and the retaining-ring or similar device 21.

22 designates a plate having the openings 23 therein, said plate being detachably mounted on the discharge end 24 of the casing 2, the upper portion of the plate 22 being provided with an inwardly-projecting lug 25, which has the recess 26 therein, which engages the upward projection or lug 27 of the casing, said lug 27 having the dog or catch 28 pivotally mounted thereon by means of the pin 29. The nose 30 of said dog engages a recess 31 in the periphery of the plate 22, whereby the latter is prevented from rotation and is detachably coupled in a simple and effective manner to the discharge end of the casing 2.

I desire to call especial attention to the feature of having the dog 28 projecting in longitudinal alignment with the forcer and having its under side 28^X extended, so as to project beyond the plate 22 in the manner seen in Figs. 1 and 3, since the under side of said dog serves as a species of wiper and prevents clogging of the food which is being chopped around the outlet-openings 23 of the plate 22, as will be apparent. The under side of the plate 22 is provided with a recessed lug 32, which is similar to the lug 25 seen in Fig. 3 and is adapted to engage the lug or projection 33 on the under side of the body 2, said lug 32 being provided with a recess 34, so that the nose of the dog 28 is adapted to engage therein with the same facility as with the recess 31.

35 designates a thumb-screw which is adapted to be screwed into the forcer 16 in the manner indicated in Fig. 1, said forcer having the cylindrical journal 36 formed thereon, which has its bearing in the plate 22, and said forcer being continued to form the squared extension 37, which engages a squared or polygonal-shaped opening in the cutter 38, whereby it will be seen that when the parts are assem-

bled, as in Fig. 1, the forcer 16 has its bearing in the stationary plate 22, while the cutter 38, mounted on the squared extension 37 of said forcer, revolves in unison therewith.

5 I desire to call especial attention to the location of the cutter 38, exterior to the plate 22. By reason of said location all of the material is cut and none of the same is left inside of the chopper, as is the case when the 10 cutter is located interiorly of the apertured plate.

40 designates a lug projecting from or cast on the side of the casing or body 2 and adapted to support the cutters 41, 42, and 43 when 15 not in use.

It will be apparent that the rotation of the forcer 16 will force the material to be chopped through the openings 23 in the stationary plate 22 and that said material will be cut by 20 the contiguous cutting edges of the cutter 38 during the revolution thereof.

When it is desired to clean the apparatus, (seen in Figs. 1 to 3, inclusive,) it is only necessary to lift the dog 28 and turn the plate 22, 25 whereupon the forcer 16, the parts 14 and 15, as well as the stationary plate 22, and the rotary cutter 38 can be readily withdrawn in assembled position or as in one piece from the body 2, while the bearing 19 of the handle re- 30 mains within the casing, thus producing a two-part chopper, as it were, which is readily accessible at all times and not liable to get out of order. The cutter 38 can be readily removed after taking off the thumb-screw 35, 35 and the plate 22 can also be readily disconnected from the forcer 16, as will be evident.

In assembling the parts it is immaterial whether the recess 31 or the recess 34 is uppermost, as the nose of the dog 28 can engage 40 either one with equal facility.

I desire to call especial attention to the fact that the contiguous faces of the cutter 38 and the apertured plate 22 are flat, whereby the same can be easily sharpened when desired 45 by simply rubbing said contiguous faces upon a flat piece of emery-cloth or similar material, so that the sharpening of the device can be much more readily effected than it can where the contiguous faces, as of the plate 22 and 50 cutter 38, are conical or arc-shaped.

Having thus described my invention, what I claim as new, and desire to secure by Letters Patent, is—

1. In a food-chopper, a casing, a forcer rotatably mounted therein, an extension on said forcer, an apertured plate mounted on the discharge end of said casing, a cutter mounted upon an extension of said forcer and exterior to said plate, a slotted lug carried by said 55 plate, a lug on said casing adapted to be engaged by said slotted lug, whereby said plate is held stationary during the action of the forcer, the latter having a bearing in said plate, a dog pivotally mounted on the first- 60 mentioned lug and located in proximity to said plate and fastening devices common to said cutter and forcer.

2. In a food-chopper, a casing, a forcer therein, a plate mounted upon the discharge end of said casing and provided with a slotted lug, a lug attached to said casing and adapted to interlock with the slotted lug of said plate, a recess in said plate, a dog pivotally mounted on the lug attached to said casing and adapted to engage said recess, the 70 said dog projecting beyond said plate and serving as a wiper, a cutter contiguous to said plate and fastening devices common to said cutter and forcer.

3. In a food-chopper, a casing, a plate 80 mounted on the discharge end thereof, interlocking devices common to said plate and casing embodying a lug projecting from the casing to engage a notch in said plate and extended beyond said plate through said notch 85 whereby rotation of said plate is prevented, a forcer, a cutter carried by said forcer and adapted to rotate in unison therewith and means for holding said plate stationary during the action of the forcer, said cutter and 90 forcer having flat or plain contiguous surfaces, a handle having its bearings rotatably mounted in said casing, means for preventing said handle from longitudinal disconnection with said casing, and means for permitting the withdrawal of the forcer, plate and 95 cutter in assembled condition from said casing without necessitating the disconnection of said handle from said casing, whereby a two-part chopper is formed.

4. In a food-chopper, a casing, a handle provided with a bearing rotatably mounted in said casing, means for preventing said bearing and handle from longitudinal disconnection from said casing, a forcer located in 105 alignment with the bearing for said handle and detachably connected therewith, a plate, a cutter mounted on an extension of the forcer exterior to and located in proximity to said plate, said plate having a notched flange embracing the casing, and a pivoted member to engage in a recess in said flange, and means for permitting the withdrawal of the forcer, plate and cutter in assembled position without disconnection of the handle from its casing, whereby a two-part chopper is formed.

5. In a food-chopper, a casing, a forcer therein, an apertured plate mounted on the discharge end of said forcer, locking devices common to said plate and to said casing and embodying a lug projecting from the casing to engage a notch in said plate and extended beyond said plate through said notch, a cutter secured to an extension of said forcer exterior to said plate and adapted to rotate in 115 unison with said forcer, a handle having a portion rotatably mounted in said casing but prevented from longitudinal disconnection therewith, and means for permitting the withdrawal of the forcer, plate and cutter in assembled condition without disconnection of said handle from said casing, whereby a two-part chopper is formed.

6. In a food-chopper, a forcer, a casing

- therefor, a handle rotatably mounted within | drawal of said forcer and cutting devices in
said casing, means for preventing the discon- assembled position without disconnection of
nection of said handle in a longitudinal di- the handle from its casing, whereby a two-
rection from said casing, interlocking devices part chopper is formed.
- 5 common to said forcer and handle, an aper- 8. In a food-chopper, a casing, a handle hav- 30
tured plate mounted upon the discharge end ing a bearing in its upper portion rotatably
of said casing, means for preventing rotation mounted in said casing, a washer located
of said plate with respect to said casing and within said casing through which the bearing
embodying a lug projecting from the casing for said handle passes, a retaining device ad-
10 to engage a notch in said plate and extended jacent to said bearing, whereby rotation of 35
beyond said plate through said notch, a cutter said handle is permitted but longitudinal dis-
connected to said forcer and fastening connec- 40
devices common to said cutter and forcer.
7. In a food-chopper, a casing, a handle pro-
15 vided with a bearing rotatably mounted there-
in, a washer contacting with the contiguous
portion of said casing and having an opening
therein through which the bearing of said
handle passes, a retaining device common to
20 said washer and bearing whereby rotation of
the handle is permitted, but the longitudinal
disconnection thereof from said casing is pre-
vented, a forcer detachably connected to said
handle, cutting devices adapted to coact with
25 said forcer and means for permitting the with-
- drawal of said forcer and cutting devices in
assembled position without disconnection of
the handle from its casing, whereby a two-
part chopper is formed.
8. In a food-chopper, a casing, a handle hav- 30
ing a bearing in its upper portion rotatably
mounted in said casing, a washer located
within said casing through which the bearing
for said handle passes, a retaining device ad-
jacent to said bearing, whereby rotation of 35
said handle is permitted but longitudinal dis-
connection thereof from its casing is pre-
vented, a polygonal opening in the bearing
of said handle, a forcer mounted in said cas-
ing and having a polygonal extension engag- 40
ing said opening, cutting devices coacting
with said forcer and means for permitting the
withdrawal of said forcer and cutting devices
in assembled position from said casing and
handle without disconnection of said handle 45
from said casing.
